CHECK CONTROLLED MECHANISM

Filed March 11, 1924

INVENTOR.

H. M. Walker

BY
Watson E. Coleman
ATTORNEY.

UNITED STATES PATENT OFFICE.

HARRY M. WALKER, OF NEW ORLEANS, LOUISIANA.

CHECK-CONTROLLED MECHANISM.

Application filed March 11, 1924. Serial No. 698,478.

To all whom it may concern:

Be it known that I, HARRY M. WALKER, a citizen of the United States, residing at New Orleans, in the parish of Orleans and State 5 of Louisiana, have invented certain new and useful Improvements in Check-Controlled Mechanisms, of which the following is a specification, reference being had to the accompanying drawings.

- 10 This invention relates to certain improvements in check controlled mechanisms and is primarily an improvement on the mechanism disclosed in my Patent No. 1,463,521 dated July 31, 1923, and it is an object of 15 the invention to provide novel and improved means under check control for operating an endwise movable member, such as the operating rack for the piston comprised in a gasoline or kindred liquid vending machine.
- 20 The invention consists in the details of construction and in the combination and arrangement of the several parts of my improved check controlled mechanism whereby certain important advantages are attained 25 and the device rendered simpler, less expensive and otherwise more convenient and advantageous for use, as will be hereinafter more fully set forth.

The novel features of my invention will 30 hereinafter be definitely claimed.

In order that my invention may be the better understood, I will now proceed to describe the same with reference to the accompanying drawings, wherein:—

- 35 Figure 1 is a fragmentary view in elevation illustrating a mechanism constructed in accordance with an embodiment of my invention and in applied position;

Figure 2 is an enlarged fragmentary view 40 partly in section and partly in elevation illustrating my improved mechanism in detail;

Figure 3 is an enlarged fragmentary view 45 of my improved mechanism illustrating certain of the parts in a second position;

Figure 4 is a sectional view taken substantially on the line 4—4 of Figure 3;

Figure 5 is a detailed sectional view taken substantially on the line 5—5 of Figure 3.

- 50 As disclosed in the accompanying drawings, 1 denotes the operating rack or member for the piston of a gasoline vending machine which extends upwardly within a housing H. The top 2 of the housing H is provided with a tubular depending sleeve or guide member 3 through which the upper

portion of the rack or member 1 works during a delivery operation. The housing H is provided with a door 4 adapted to be locked in closed position, said door providing means whereby access may be had to the mechanism arranged within said housing H. 60

Extending inwardly and downwardly of the housing H is a chute 5, the lower end portion of which communicates with the inner end portion of a substantially horizontally disposed runway 6. The inner end of the runway 6 is open to provide communication with the collecting receptacle 7 supported within the housing H and which receives the checks ejected from the runway 6 as will hereinafter be explained. 65

The top wall of the chute 5 immediately adjacent the runway 6 is cut away, as at a, to facilitate the ejecting of the check C and the requisite coaction of said check with the holding means associated with the rack or holding member 1. The portion of the runway 6 immediately below the lower end of the chute 5 is of restricted diameter, as is particularly illustrated in Figure 5, so that the check when received therein is maintained in substantially a vertical position in order that said check may effectively perform the function desired. 70

Snugly working within this restricted portion of the runway 6 is a plunger 8 which is constantly maintained at the limit of its inward movement by an expansible member 9. This member 9, as herein disclosed, comprises a coil spring encircling the outwardly directed step 10 carried by the plunger 8, said spring being interposed between the inner end of the plunger 8 and the cap 11 or the like closing the outer end of the runway 6. The stem 10 is of a length to extend exteriorly of the housing and said extended end portion is provided with a knob 12 or the like to facilitate the desired manipulation of the plunger 8 and particularly to retract the same. 80

14 denotes a substantially V-shaped dog having its apex portion pivotally supported, as at 15, by a side wall of the housing H, the arms of said dog alternately engaging the ratchet wheel 16. One of said arms serves to hold the rack or member 1 against endwise movement in one direction and the second arm serves to hold the rack against endwise movement in the opposite direction. 100 Extending outwardly from the pivoted or apex portion of the dog 14 is an arm 17. 110

Bearing against the outer end of the arm 17 is an end portion of an expansible spring 18, the opposite end of said spring bearing against a block 19 extending laterally from the lower part of the chute 5. This spring 18 as the arm 17 passes beyond the horizontal center serves to maintain either of the arms of the dog 14 in proper engagement with the teeth of the wheel 16 whereby 10 the rack or member 1 is held against endwise movement in one direction yet free to move in the opposite direction until the second arm of the dog 14 is engaged with the teeth of the ratchet wheel 16.

15 The outer end portion of the arm 17 rotatably supports at one side thereof a roller 20 which, when the lower arm of the dog 14 is engaged with the teeth of the wheel 16 to hold the rack 1 against upward movement, is positioned in close proximity to the inner end of the runway 6 and in the path of travel of the check C when within the runway 6 in advance of the plunger 8 so that as the check C is forced under the 20 roller 20, the lower arm of the dog 14 will be freed from the ratchet wheel 16 to permit the rack to have upward endwise movement. During this movement, the second or upper arm of the dog 14 is operatively engaged with the teeth of the ratchet wheel 16 to hold the same against reverse endwise movement. This position of the dog 14 is maintained by the spring 18 as the check C will coat with the roller 20 to 25 cause the arm 17 to be swung upwardly beyond a horizontal center. As the check passes under the roller 20, it is received within the receptacle 7.

Engaged with the rack or member 1 is a 40 conventional gear or pinion 21 operated exteriorly of the housing H by the crank 22 or its equivalent. Extending from the dog 14 toward the rack or member 1 and substantially coplanar with the arm 17 is a spring arm 23. This arm 23 overlies a side of the rack or member 1 and is in the path of travel of a pin 24 carried by the lower portion of the rack or member 1. As the rack or member 1 moves upwardly, the pin 45 24 comes into contact with the spring arm 23 resulting in the upper arm of the dog 14 being disengaged from the wheel 16 and the lower arm of said dog engaged with said wheel 16 whereby the rack or member 1 is held against further upward movement or 50 free to be moved in the reversed direction.

The pin 24 is adjustably engaged with the member or rack 1 through the longitudinally disposed slot 25. By adjusting the position of the pin 24 lengthwise of the member or rack 1, the length of the upward stroke of the rack or member 1 may be regulated as desired so that the quantity of gasoline or other liquid delivered during the 55 upward movement of the rack or member

1 may be varied and particularly as may be necessitated by the cost or price of the gasoline or the like.

With a gasoline station or the like equipped with a mechanism constructed in accordance with an embodiment of my invention, the station may be operated upon the deposit of a coin of desired value within the chute 5 so that a customer can help himself without the assistance of an attendant 70 and which is particularly desirable during the hours when it is not convenient for the owner to have his place of business open.

It is to be understood that after the check or coin C is deposited in the chute 5, the plunger 8 is moved by pull upon the stem 10 a distance sufficient to permit the check to drop in the runway 6 in advance of the plunger 8. The stem 10 is then released and the tension of the spring or member 9 is sufficient to force the check or coin C under the roller 20 and thereby operate the dog 14 to permit the rack or member 1 to be moved upwardly upon requisite operation of the operating member or crank 22.

When the dog 14 is moved into a neutral position or in a position with both of the arms free from the wheel, the pump can be operated without the use of the check controlled mechanism.

As is particularly illustrated in Figure 4, the wheel 16 and the gear or pinion 21 are fixed to a common shaft 26 with the wheel 16 positioned to one side of the member or rack 1 and overlying said side face.

It is also to be noted that the free extremities 14' of the arms of the dogs 14 are disposed on slight inward curvatures so as to have more effective engagement with the wheel 16.

As particularly illustrated in Figure 4, the wheel 16 overlies one of the side faces of the rack 1, while the arm 23 overlies the opposite face of the rack, and it is apparent by this arrangement that the wheel 16 and arm 23 not only perform the hereinbefore referred functions but also serve to provide further means to prevent lateral play of the rack.

From the foregoing description it is thought to be obvious that a check controlled mechanism constructed in accordance with my invention is particularly well adapted for use by reason of the convenience and facility with which it may be assembled and operated, and it will also be obvious that my invention is susceptible of some change and modification without departing from the principles and spirit thereof and for this reason I do not wish to be understood as limiting myself to the precise arrangement and formation of the several parts herein shown in carrying out my invention in practice except as hereinafter claimed.

I claim:

1. In combination with a rack pump rod for a gasoline tank, a manually operated pinion actuating the pump rod, a toothed wheel rotating with the pinion, said toothed wheel being of a diameter to overlie one of the faces of the pump rod, a substantially V-shaped dog pivotally supported adjacent to and on the opposite side of the pump rod from the pinion, the axes of the dog and pinion being aligned in a direction transverse of the pump rod, the arms of the dog alternately engaging the toothed wheel, an arm secured to the apex portion of the dog and overlying the face of the pump rod remote from the toothed wheel, check controlled means for swinging the dog in one direction, and means carried by the pump rod for swinging the dog in the opposite direction.
2. In combination with a rack pump rod for a gasoline tank, a manually operated pinion actuating the pump rod, a toothed wheel carried by and rotating with the

pinion, said toothed wheel being of a diameter to overlie one of the faces of the pump rod, a substantially V-shaped dog pivotally supported adjacent to and on the opposite side of the pump rod from the pinion, the axes of the dog and pinion being aligned in a direction transverse of the pump rod, the arms of the dog alternately engaging the toothed wheel, an arm secured to the apex portion of the dog and overlying the face of the pump rod remote from the toothed wheel, check controlled means for swinging the dog in one direction, and means carried by the pump rod for swinging the dog in the opposite direction.

In testimony whereof I hereunto affix my signature.

HARRY M. WALKER
